UNITED STATES PATENT OFFICE.

JOHN G. LEWIS, OF ST. LOUIS, MISSOURI.

HEM OR SEAM FOR SEWED ARTICLES AND METHOD OF MAKING SAME.

1,179,945.

Specification of Letters Patent.

Patented Apr. 18, 1916.

Application filed December 8, 1914. Serial No. 876,102.

To all whom it may concern:

Be it known that I, JOHN G. LEWIS, a citizen of the United States, residing in St. Louis and State of Missouri, have invented 5 certain new and useful Improvements in Hems or Seams for Sewed Articles and Methods of Making Same, of which the following is a specification.

My invention relates to a hem or seam for 10 sewed articles and method of making same.

In general my invention has for its object to provide an improved concealed-effect felling seam adapted for production by sewing machine, and a particular object of 15 my invention is to improve upon the seam structures shown and described in my co-pending application, Serial No. 502,878, filed June 18, 1909. In said application I have described and claimed a seam invention 20 wherein an edged layer of material may be secured to a subjacent base layer by a single row of stitches, entering the superimposed layer and emerging from the base layer on the same side of the work and preferably 25 "blind" in the base layer, and with the running connections of the needle thread, between adjoining stitches, overcast across the edge to engage the keying connections, so that for every needle thrust there results 30 the laying of both (a) the goods-penetrating loop structure, properly keyed, securing the goods layers together, and (b) an overcast needle-thread bight or loop springing from the points of needle entrance on the previous 35 and instant stitches, running over the edge of the superimposed layer, and retained by the keying connections at the point of emergence of the instant stitch from the base layer. In my said application I have 40 also indicated that this overcasting of a needle-thread bight or loop may be effected with different sorts or types of stitching,—that is to say, lock stitching and chain stitching;—and with respect to the present 45 improvement the same thing is true.

In all of the embodiments of my invention shown in my aforesaid application, the bend or crest of each overcast bight of 50 needle thread passes under the keying connections from the inner side toward the outer side of the line of keying connections.

The specific object of my present invention is to provide a seam, and method of 55 making the same, whereby the crest of each overcast bight or loop may pass under its keying connections from the outer side in-

wardly. That is, in accordance with my present invention, the keying connections lie inside of, or nearer to the points of stitch-entrance than the limbs of the overcast 60 bight, the crest of which passes in under the keying connections partially to encompass the point of stitch emergence from the base layer. In this way I am enabled to increase the facility for, and tendency to, conceal- 65 ment of the keying connections or thread runs under the edge of the superimposed layer, thus enhancing the desirability of the seam-structure for many kinds of work, and increasing its beauty. 70

In the accompanying drawings I have illustrated,—in such grossly exaggerated fashion as seems best calculated for ready understanding of the seam structure and a 75 method of its production,—embodiments of my present invention in both lock stitch and chain stitch seams.

In said drawings—Figure 1 is a perspective view showing a lock stitch form of seam in the course of the making thereof, 80 the illustration, of course, being diagrammatic and the plies of material shown being illustrated as partly pulled apart, and with the threads loosened, the more clearly to show the thread concatenation. Figs. 2 and 85 3 represent successive stages in the formation of the stitch shown (to the left) as partially completed in Fig. 1. Fig. 4 is the section along the diagonal line of one of the 90 stitches. Fig. 5 is a view similar to Fig. 1 but showing a chain stitch formation.

In the seam construction shown 10 indicates a base layer of fabric and 11 a superimposed layer preferably having a turned-under edge 12 so that the edge portion of 95 said layer is composed of two plies 11^a and 11^b. This typifies the condition presented under many circumstances in clothing manufacture, but it will be apparent that my invention is not dependent upon the number 100 of plies or layers of superimposed material to be connected to the base layer.

Each stitch *a*, *b*, *c*, etc., enters the superimposed layer a little back from the edge, passes downward through the superimposed layer and into and out of the base layer, emerging on the same side of the work that it enters. In the base layer the stitch is preferably blind, that is, does not show through to the "fair" side or underside of 110 the work. And preferably the stitches are made diagonally to the edge. The needle

thread portions that connect the points of needle entrance into the work I will term the "needle-thread running connections"; and the thread runs that connect the successive points of needle emergence from the base layer, and key the penetrant loops of needle thread, I will term the "keying connections".

Assuming a series of stitches *a*, *b*, and *c* to be made, each entering the superimposed layer at 14, passing downward therethrough into and out of the base layer to emerge at 15, a succession of needle thread running connections 16 will connect the several points of entrance 14 and a succession of keying connections 17 on the base layer will connect the points of stitch emergence 15, these keying connections 17, in a lock stitch seam construction, consisting of a run of bobbin thread, and, in a chain stitch construction, consisting of the enchain loops of needle thread. Either form of construction, providing a series of keyed penetrant loops, secures together the two layers. The successive needle thread running connections 16 are overcast across the edge, each to form a bight or loop, springing from the points 14 of entrance of two successive stitches, and having its crest engaged with and positioned by the keying connections at the point of emergence of the last-made of said stitches from the base layer. Generically such overcasting of the needle thread bight is shown in my aforesaid application, but in the embodiment of my present invention the limbs 19-19' of the overcast bight 16 pass down outside of the keying connections 17 and the crest 20 passes inward under said keying connections and around the point of emergence of the stitch from the base layer. In consequence of this arrangement it will be apparent that tension applied to the stitching threads may readily draw the edge of the superimposed material 11 over beyond the line of keying connections 17 entirely to conceal said keying connections under the edge, and furthermore as will be apparent from Fig. 4, further rolling over of the edge (should it be desired) by a pressing operation, is facilitated. In the completed article the thread 17, raised by the reversed loops 20, will tend to lie against the superimposed material, if the stitching is fairly tight, and hence the two threads may for neat effect, be both of a color to match the superimposed layer.

The preferred methodic operations by which I obtain this thread arrangement are as follows: The keying connection from the preceding stitch (whether, as in Fig. 1 the keying connection is supplied by a bobbin thread, or, as in Fig. 5, by chain loops of needle thread) is laid inside of the line of needle-emergence-points 15 and is carried

rearward, or counter to the feed, (shown by the arrow), beyond the predetermined point of needle emergence. (A mechanical holder, *h*, is shown in dotted lines for clear understanding). The needle thread connection 16, running from the point of entrance of instant stitch, *c*, back to the preceding stitch, *b*, is then overcast across the edge and laterally beyond said keying connection, and the bight or loop so overcast is given a half twist such that its anchored limb 19, leading to the previously completed stitch, lies under its "spool" limb 19' (that is, the limb that leads through the eye of the needle to the spool). The needle, *n*, on its thrust, emerging under and outside of or laterally beyond the keying connection 17, passes through the half twisted overcast loop and presents the needle thread loop 21 to the loop taker; and then the keying thread structure is locked or enchain with the needle thread loop 21 in any usual fashion. Laying the keying connection so that it passes to the inner side of (in a transverse direction) and beyond (in linear direction) the point of needle-emergence, before locking or enchain said keying connections with the penetrant needle thread loop 21, results in giving the keying connections a back-turn, as it were, half around the anchored limb 19 of the overcast bight, which itself has been thrown under the limb 19' by reason of the half-twist of the overcast bight. Thus, as will best be appreciated from examination of Figs. 2 and 3, as the threads are drawn up, the back turn of the keying connections straightens out, carrying the anchored limb 19 of the overcast bight along toward the side of its anchorage in the preceding stitch, untwisting the half-twisted bight, and so giving to the inter-engaged overcast bight and the keying connections their intended relative positions such that the bight-crest passes inwardly under the keying connections.

Having described my invention, what I claim is:—

1. A seam involving a body of material and a row of stitches therein having their entrance points connected by needle thread running connections and their emergence points connected by keying connections, overcast bights in the needle thread running connections, each formed between two successive stitches, each having its crest positioned by said keying connections at the emergent point of the last made one of the said two successive stitches, and each having its limbs passing outside of, and its crest passing inwardly under, said keying connections.

2. A hem or seam for sewed articles comprising a base layer of goods, a superimposed layer of goods, presenting an edge, and a row of stitches connecting said layers,

each stitch entering the superimposed layer and emerging from the base layer on the same side of the work, the emergent ends of said stitches connected by keying connections, and the entrant ends of said stitches connected by needle thread running connections, each said running connection forming a bight, overcast on the said side of the work, with its crest passing under the keying connections in an inward direction and partially encompassing the point of emergence of one of said stitches.

3. A blind-stitch concealed-effect felling seam comprising the base layer, a superimposed layer having a turned under edge, and a single row of stitches connecting said layers, said stitches entering the superimposed layer and emerging from the base layer on the same side of the work, said stitches having their emergent ends connected by keying connections lying along the base layer under the edge of the superimposed layer and having their entrant ends connected by running connections of needle thread, each said running connection between two stitches forming a bight overcast across the edge and positioned by the keying connections at the emergent end of the last made of said two stitches, the crest of each said bight passing under said keying connections inwardly, so that said keying connections lie inwardly from the limbs of the overcast bight.

4. In the art of stitching goods with a reciprocating needle to unite the goods-layers by a series of keyed stitches, the steps which con-

sist in overcasting a half-twisted loop of needle thread from between the points of entrance of successive stitches to receive the needle on its emergence in forming the last said stitch, and giving the keying connections from the previous stitch a back-turn about one limb of said half twisted loop before engaging said keying connections with the needle carried loop.

5. The improvement in the art of stitching goods with a reciprocating needle to unite the edge portion of a superimposed layer to a base layer by a series of keyed stitches, which consists in overcasting the needle carried thread, between successive needle penetrations, with a half twist laying the anchored limb of the bight under the other limb thereof, and giving the keying connection leading from the preceding stitch a back turn leading it inwardly from, and then out around, the anchored limb of said bight, before engaging the said keying connection with the needle carried thread-loop, whereby setting of the stitch may dispose the overcast bight with its crest passing inwardly under the keying connections and around the point of stitch emergence.

In testimony whereof I hereunto set my hand in the presence of two subscribing witnesses.

JOHN G. LEWIS.
